UNITED STATES PATENT OFFICE.

MAURICE B. DIETZ, OF HOUSTON, TEXAS.

REFRIGERATOR-CAR.

1,278,313.

Specification of Letters Patent. Patented Sept. 10, 1918.

Application filed January 3, 1916, Serial No. 69,779. Renewed March 19, 1918. Serial No. 223,467.

To all whom it may concern:

Be it known that I, MAURICE B. DIETZ, a citizen of the United States, residing at Houston, in the county of Harris and State 5 of Texas, have invented certain new and useful Improvements in Refrigerator-Cars, of which the following is a specification.

This invention relates to new and useful improvements in a refrigerator car.

10 The object of the invention is to provide a car of the character described containing ice receptacles and equipped with pipe coils through which the brine given off from the ice may be circulated around the walls of 15 the car, and further provided with means for circulating the air around said pipes and throughout the car.

With the above and other objects in view the invention has particular relation to certain 20 novel features of construction, operation and arrangement of parts an example of which is given in this specification and illustrated in the accompanying drawings, wherein:—

25 Figure 1 is a horizontal sectional view of the car,

Fig. 2 is a vertical sectional view thereof,

Fig. 3 is an enlarged fragmentary side elevation thereof, and

30 Fig. 4 shows a view of a universal coupling connecting the sections of a drive shaft employed in the device.

Referring now more particularly to the drawings wherein like numerals of reference designate similar parts in each of the figures the numeral 1 refers to the car having at each end thereof ice receptacles 2, 2, beneath which are the brine receptacles 3, 3 arranged to receive the brine given off from 40 the ice, said last mentioned receptacles being connected by means of the conduit 4. Leading from the bottom of one of the brine receptacles is the pipe 5 which is coiled around underneath the roof of the car and returns 45 to and discharges into the upper part of said receptacle 3. The car is mounted upon the usual trucks 6, 6, fixed to the axle of one of which is the sprocket wheel 7 which drives the sprocket chain 8, which in turn operates 50 over and drives the sprocket wheel 9, this last mentioned wheel being mounted in a suitable bearing 10 carried by said truck. The inner side of the sprocket wheel 9 has a bevel gear face 11 which meshes with and 55 drives the bevel gear wheel 12 fixed upon the lower end of the drive shaft. This shaft

is formed of sections 13, 13, 13, which are united by means of universal couplings 14, 14, and said shaft has suitable slip joints as 15, 15 provided to permit a certain 60 amount of variation in the length of the shaft.

Projecting inwardly from one side of the car is the spindle 16 whereon is mounted the bevel gear wheel 17 which is in mesh with and driven by a bevel pinion 18, fixed upon the upper end of said drive shaft and the pulleys 19 and 20 are integral with said gear wheel 17 and over these pulleys operate the respective belts 21 and 22, the former of 70 which drives the pump 23 and the latter of which drives the fan 24. This pump is provided to drive the fluid through the pipe 5 and the fan is connected to one end of the air pipe 25. This last mentioned pipe extends along between the coils of the pipe 5 and is provided with a row of lateral orifices 26 along each side thereof. When the car is in motion the mechanism just described will be driven from the trucks thereof and the pump 23 will operate to force the cooling fluid through the coil pipe 5 and deliver it back into its original receptacle while the fan 24 will operate to drive the air through the pipe 25 and out through 75 the orifices 26 and a current of air will be constantly circulated throughout the car carrying with it the cool air surrounding the coils of the cooling pipe 5, thus utilizing more nearly the entire value of the ice and giving additional refrigeration to the car 80 thus equipped.

What I claim is:

1. A car mounted upon trucks and having a receptacle containing a cooling fluid, a conduit communicating with said receptacle and passing through the car, a pump for driving the fluid through said conduit, an air pipe having discharge orifices arranged adjacent said conduit, a fan for forcing the air through said pipe against said conduit, and means in operative connection with said trucks and driving said pump and fan. 95

2. A car mounted upon trucks, an ice receptacle arranged at each end thereof, a brine receptacle in communication with each ice receptacle; said brine receptacles being connected, a fluid conduit leading from the lower portion of one of said brine receptacles and being coiled adjacent the wall thereof and returning to and discharging into the upper portion of said brine receptacle, a 105 110

pump for forcing the fluid through said conduit, an air pipe having discharge ori-
fices arranged adjacent the coils of said
pipe, a fan for forcing the air through said
5 pipe and against the conduit and means in
operative connection with one of said trucks
and driving said pump and fan.

In testimony whereof I have signed my
name to this specification in the presence of
two subscribing witnesses.

MAURICE B. DIETZ.
